AIR HEATER

William E. Jones, North Hollywood, Calif.

Application October 30, 1933, Serial No. 695,893

4 Claims. (Cl. 126—127)

This invention relates to air heaters and same has particular reference to heaters designed primarily for use in connection with open fireplaces, and an object of the invention is to provide a heater of this character which shall be simple and inexpensive in construction, attractive in appearance, strong, durable and highly efficient in operation, and one which will be portable and so designed and constructed that it may be quickly and conveniently applied to any open fireplace of well known form.

I am particularly concerned with those novel features of construction by means of which separate forms of heating agents or fuels may be employed and co-ordinated or combined with each other so as to produce an abundance of heated air within a comparatively short period of time and at low operating cost.

An essential object of the invention resides in a heater organization by means of which a large percentage of heat, heretofore wasted by a discharge thereof in the chimney of the fireplace, will be distributed into the space to be heated, and among certain features which characterize my invention are those which permit the heater to be employed according to conditions existing at the particular place of its installation. That is to say, (1) when the heater is to be used in mountainous regions or other places where gas is not available, resort may be exclusively had to the use of logs or other firewood; or (2) when the use of logs or other firewood is not desirable, one may resort exclusively to the use of gas; or (3) when conditions permit, and it becomes desirable, both wood and gas can be used, and with a result far superior to that heretofore attained with the prior well-known forms of air heaters. I have thus provided an efficient organization of functional features which co-act to produce a heated condition of air in the shortest practicable period of time, and, incidentally, I have so designed and constructed the several parts of my heater that different forms of fuel may be used singly or together as the occasion permits or necessitates. For instance in apartment houses and some types of dwelling places, open fire places are primarily designed for ornamental purposes. It would not be harmful to burn gas or electricity in such fireplaces, but it would not be advisable in many instances to resort to the burning of coal, logs, or firewood therein. My invention readily adapts itself to these conditions as they exist in the various types of fireplaces, and I have accordingly constructed and designed the invention so that any one of the individual

heating devices herein employed may be operated with the highest measure of efficiency.

Another important object is directed to those certain features which are productive of a heater organization which will harmonize with the fireplace and mantel layout with which it is used, and which, when associated therewith, will allow the maximum amount of heat and light to enter the room from the grate of the fireplace.

Another important object is to provide means for effectively and positively shunting part of the flame and hot gases through the heater directly from the grate and discharging same by means of the heater flue to a point at least to the fireplace throat and in utilizing these gases to heat the radiating surfaces of the heater.

I propose further to remove the heat from the radiating surface of the heater by the action of an air current which flows by convection through the system employed, thence into the space to be heated, whereby to utilize the heat content of the combustion gases instead of allowing their direct escape to the chimney as was heretofore largely the case.

Another object of the invention is to provide operatively co-ordinated heat distributors and circulators, and means for rendering one thereof wholly inoperative at the will of the user. This is highly important because it enables the user to positively confine all the draft to the heat source being employed or to allow partial draft to both sources when it is desired to use both the grate fire and the gas fire simultaneously.

A still further object of the invention is to provide novel means for accelerating the movement of the heated air through the system.

Another object is to provide means between the grate of the fireplace and the heat distributing unit of the system which is so constructed as to prevent loss of heat by radiation during the time that the heat is being conducted into the system.

A still further object is to provide a heater wherein use is made of a conventional Bunsen type of burner whose port area is such as will be conducive of a maximum port velocity such as will be consistent with quietness of operation of the heater and which will allow for proper mixture of air and gas to insure proper combustion.

Another object is to provide a heater which will greatly increase the rate of radiation at the point of combustion of the gases and cause the gases to find rapid ingress to the secondary distributor of the system but at a greatly reduced temperature. It is by reason of the novel manner employed for utilizing the combustion gases

that large variations in gas consumption can be had and with little variation in heating efficiency. A decidedly novel feature of construction of certain parts employed resides in the provision of an internal element or radiant of refractory material contained within a dome or radiant of heat resistant material, the two co-acting to provide an effective combustion chamber. I find that the rate of radiation from the external dome is so great that little variation in its area will cause more or less heat to pass into the secondary distributor or tubes of the system. Through variations in the size of the refractory element relative to the internal area of the aforesigned dome, large variations in temperature of the dome can be obtained. To make this possible, I construct the dome of thin heat-resistant material such as ferrous alloy or the like, and the refractory element I preferably construct of fire clay or some suitable well-known material possessing a high degree of radiating property capable of withstanding high heat.

Additional novel features of my invention will hereinafter be more fully pointed out and definitely claimed.

In order that my invention may be fully understood by those skilled in the art, I will now proceed to describe the same with reference to the accompanying drawings, in which

Figure 1 is a view partly in vertical section and partly in elevation of the heater;

Figure 2 is a horizontal section taken on line 2—2 of Figure 1;

Figure 3 is a horizontal section taken on line 3—3 of Figure 1;

Figure 4 is a vertical section taken on line 4—4 of Figure 1;

Figure 5 is a vertical section taken on line 5—5 of Figure 1;

Figure 6 is a vertical section taken on line 6—6 of Figure 1.

In carrying the invention into practice, I have schematically illustrated an application of my invention to an open fireplace F of usual construction, and, therefore, of a design to readily adapt itself to my improved form of heater assembly or portable structure A.

At 10 is illustrated a substantially U-shaped grate bar, on the limb or branch 11 of which is mounted a plate or ash shield 12, the said grate bar having supporting feet 13 for maintaining the said plate or shield in a flat horizontal position and spaced apart from the bottom wall of said fireplace, as shown in Figure 4 of the drawings.

The portable heater assembly or structure A is so designed and constructed that same is adapted to occupy a position almost entirely at the front or exterior portion of the fireplace, and same, with other parts which I will fully describe presently, includes an ornamental column or riser 14 at the left hand end of said assembly or structure, and at the right hand end of said assembly is a riser 15 which, like the riser 14, is also ornamental. But this last said riser, as will be seen presently, is also functionally useful for the purpose of satisfying certain objects and operations of the invention, as will be pointed out in the appended claims. I have, therefore, elected to specifically call this last said riser an air distributor by means of which warm air may be distributed into a room to be heated. These risers 14 and 15 are hexagonal in transverse section, as clearly illustrated in Figures 2 and 3 of the drawings, and they preferably constitute

fixed parts of an intermediate connecting portion 16 of the structure A whose length is such that it almost wholly extends from one side of the fireplace to the other side thereof, as properly shown in Figure 2. In said Figure 2, it will also be noted that the said risers 14 and 15 extend forwardly and laterally with respect to the open front of said fireplace, so as to occupy acute angular positions at the front of the fireplace and to overlap or extend over the vertical sides of the fireplace opening. The entire bottom of the structure just referred to is open and same is adapted to find operative support upon the floor, as shown both in Figures 1 and 4. The riser 14 is provided with a horizontal partition 17 so as to prevent said warm air from escaping from the upper end of said riser. However, warm air is adapted to be contained in the riser at a point therein beneath the partition 17 and to be placed in motion and distributed to the riser 15 in a manner and for a purpose to be hereinafter referred to. Each of the said risers 14 and 15 is provided with exteriorly positioned ornamental air ducts 18 whose lower ends are open as at 19, to permit air to enter said ducts from a point adjacent to the floor of a room and to enter the hollow assembly structure A by way of the air intake passages 20, the latter formed in the inner walls of said ducts at a suitable elevation above the floor line. The purpose of this construction is to provide for the operative admission of air to the system and a subsequent heating of this air and a distribution thereof to the room from the riser 15. Now it will be observed that each of the risers is provided at its upper end with an ornamental grill 21 but only the grill of the riser 15 is intended to function in co-action with other functional features of my invention; that is to say, the major part of the riser 14 serves primarily to contribute to a balanced or symmetrical outward appearance of the structure A.

Contained within the structure A and occupying a horizontal position therein is a heater unit, and same is largely characterized by parallel air conduits or internal radiating tubes 22—22. These tubes are, in turn, operatively mounted within a hot air drum or external radiator 23 into which hot combustion gases are adapted to be discharged and to be placed in continuous motion and always wholly isolated from air to be heated, during passage of the latter through said tubes.

The respective ends of the tubes 22—22 telescopically fit over short collars 24 on the respective headers 25—25, and the latter are shown as joined at 25a to the respective ends of the intermediate section 26 of the drum 23. A stay bolt 27 functions to tie the aforementioned headers to said intermediate section of the drum in a manner to provide gas-tight connections between the headers and said intermediate drum section 26 at the joints 25a.

In the lower portion of the riser 15 is a combustion chamber assembly or unit 27a which consists of inner and outer radiants 28 and 29. The radiant 28 is in the form of a hollow dome and same is preferably constructed of chromium steel of very thin gauge, and same is adapted to be placed directly over a flame so that hot combustion gases will ascend into said dome. The radiant 29 is also dome-shaped and same is of a size with respect to that of the outer dome 28 to provide an intervening combustion space between the internal surfaces of said outer

dome and the external surfaces of said internal dome. The dome 29 is constructed of refractory material, and same is formed at one side with a passage 30 which opens both to the space 5 between the respective domes and to the discharge chamber 31 in the refractory dome 29. At 32 is a gas burner of the Bunsen type, the same including a horizontally disposed arcuate head 33 having jet orifices 34. This burner is 10 positioned beneath the dome 28 and the arcuate construction of the head 33 serves to cause the jet orifices 34 to align vertically with the aforesaid intervening space between the said domes 28 and 29. The port area of this burner is so 15 calculated as to produce the maximum port velocity consistent with quietness of operation of the burner, and to allow for good air mixture within the effective combustion zone of the structure. The flame from this burner is thus 20 compelled to pass in an upward direction so as to play against and impinge upon the inner surface of the thin metal dome 28, which latter may therefore be termed the primary radiant. It then is compelled to travel in a downward direction 25 at the opposite sides of the dome, so that same will enter the chamber 31 by way of the passage 30, whence said combustion gases leave the chamber 31 and discharge into the drum 23 at the base of the riser 15. To make this possible, 30 the chamber 31 connects with said drum through a transfer duct or elbow 35, and co-operable with the latter is a control valve 36 whose purpose I shall explain presently.

In practice, I find that a burner assembly 35 such as I have just described will consume about 20 cubic feet of gas (1,000 B. t. u. per cubic foot) per hour. The refractory dome 29 guides the hot gases to the very top of the outer dome 28 and at the same time radiates and reflects heat 40 to the outer dome, thus greatly increasing the temperature of its surfaces. I find also that the actual surface temperature of said dome ranges from 800° F. to 1,500° F. The design 45 of the combustion chamber and the co-acting burner bring about the other necessary requirements for high flame temperature, viz., fast and complete combustion and complete control of secondary air. The construction is such that I am able to reduce the necessary amount of 50 direct radiating surface for a given fuel consumption, and to reduce the oxidizing effect on the radiating surfaces due to the lower temperature of the gases after leaving the outer dome 28. The arrangement is productive of a highly efficient unit of minimum proportions, the life of 55 which should be appreciably long, and it will not be subject to premature deterioration or make necessary any frequent replacement of the parts employed.

60 A gas valve 37 connects with the Venturi tube 38 of the burner head 33. At 39 is shown a horizontally swinging lever to which the operating rod 40 for the valve 36 is loosely connected at 41, the said rod having jointed connection 65 with the slidably mounted stem 42 of said valve. A sprocket gear 43 on the rotary stem 44 of the valve 36 meshes with a sliding rack bar 45, and as shown, said rack bar passes under the control lever 39 and the offset end 46 thereof 70 is mounted in a guide 47. The stem 44 can be manually turned by the handle 37a. At one side of the lever 39 and formed on said rack bar is a lug 48. The angular portion 49 of the rack bar is designed to co-act with the guide 47 so as

75 to limit the opening movement of said valve 36. The rack bar is formed with a longitudinal series of sprocket openings 50 adapted to intermesh with the teeth of said sprocket gear 43, and as shown in top plan in Figure 3, the actuating 5 end of said rack bar passes over the sprocket gear and the bar is sufficiently resilient to cause same to be under constant tension to insure proper intermeshing engagement of same with said sprocket gear. A gas supply tube 51 operatively connects with the valve 37 by means of which gas may be discharged into the Venturi tube 38 at the air orifice 52 of said burner 37. It is intended that when the valve 37 is turned on the valve 36 will be opened, and when the 10 gas is turned off, said valve 36 remains open so that combustion gases may be completely vented. In Figure 3, the valve 37 has been fully opened. The lug 48 has engaged the free end of lever 39, and the valve 36 thereby moved to uncover the 15 discharge end of elbow 35. The portion 49 will have engaged the stop 41. When the handle 37 is turned clockwise to cut off the gas supply to burner 33, valve 36 will remain open and can be subsequently closed by manually operating 20 the lever 39.

A fire tube 53 extends into the fireplace from the intake elbow 54, the latter extending from the rear side of the intake header 25 at the right hand end of the aforesaid combustion 30 drum. This tube is constructed of fire clay and same is encased within a metal sheath 55. The tube is of large internal diameter and same extends diagonally into the fireplace and same is formed with a large intake opening 56 which 35 occupies a position parallel with respect to the inner edge of the ash shield 12 of the grate bar 10. The said inner edge of the shield 12 projects sufficiently to one side of a vertical line traversing the opening 56 to protect same from 40 ashes falling from the grate. In the intake elbow 54 is a valve 57 having a manually controlled adjusting means whereby the valve may be opened or closed as desired. When said valve is 45 opened, the hot gases from the grate of the fireplace are free to enter the combustion drum 23. The outlet header 25 at the left hand end of the drum 23 is provided with a discharge duct 58 which opens into a suction inducing flue 59 which latter is extended in an upward direction 50 towards the throat of the fireplace, so that a constant suction will be set up in the combustion drum 23 to thus cause the combustion gases to be 55 continuously conducted or drawn away from the said drum and discharged upwardly into the fireplace by way of the open end 60 of said flue 59.

Whenever it may be desired to accelerate the movement of air through the tubes 22-22 from the lower portion of the riser 14, an electrically driven fan 61 may be set in motion. It functions to produce a greater air velocity so as to thereby reduce the stratification of the warm air in the room and greatly increase the effectiveness of the available heat.

On the supporting ledge 62 for the dome 28 is 65 an arcuate double-walled radiation shield 63, the same being concentrically related to said heater and slightly spaced apart therefrom. It extends vertically a considerable distance above the heater, as shown in Figure 1 of the drawings. The grill 21 of the warm air distributor or riser 15 is formed with vertically disposed warm air discharge passages 64, the center one of which is co-axially related to said dome 28. It is due to the last described relationship of 70 75

- the parts that I am able to cause the warm air to move with uniform velocity. Heat radiating from the thin-walled metal dome 28 will be absorbed by wire mesh material 65 which forms a lining for the riser 15, and between said mesh material and the inner walls of the riser is a packing 66 of insulating material. This construction functions to dissipate the heat to an upwardly moving air stream within said riser.
- Extending in a horizontal direction over the top of the assembly A is a top enclosure panel 67 between the spaced apart parallel walls of which is a packing of heat insulating material 68. This panel connects with the drum 23 by means of suitable brackets 69. Extending downwardly from the rear side of said panel is a wall 70 which terminates at the base of the assembly A. In this manner, warm air is permitted to flow through the space 71 which embraces the drum 23, and as illustrated in Figure 1 of the drawings, said space 71 constitutes a lane of communication between the lower part of the riser 14 and the lower part of the warm air distributing riser 15.
- A wire screen 72 rises from the panel 67 and the side edges of said screen are slidably received in the vertical guides 73 on the respective risers 14 and 15. By reason of this construction, a maximum amount of heat and light may readily enter the room from the grate of the fireplace. It will be remembered, however, that a large part of the heat from the grate will be shunted through the drum 23 by the action of the suction or draft flue 59, the suction being sufficient to cause the hot gases to be continuously drawn through the fire tube 53 and immediately discharged into said drum 23.
- I have now fully described the essential structural features of the invention and to a very material extent the function and operation thereof, and I shall, therefore, refer only briefly to a more or less general description of the more essential operations which I desire to stress.
- The heat generated by the various radiating surfaces of the structure is removed by a continuous air current which flows by convection through the right hand riser 15. When the gas burner 33 is exclusively operating, it is intended that the heater unit 27 be entirely cut off from the fire tube 53 so as to prevent loss of draft at the burner and an undesirable influx of cold air to the combustion drum 23. Because of the position of the burner unit 27 in the riser 15, it manifestly follows that the highest temperature will be produced at the point of outlet of the warm air at the very top of the said riser.
- I wish to particularly stress the novelty existing in the general make up of the heater unit 27 which essentially consists of the co-acting radiants 28 and 29, the former of which I have elsewhere referred to herein as the internal radiant and the latter as the external radiant. By means of this internal radiant, large variations in gas consumption can be had with little variation in heater efficiency. The rate of radiation from this external radiant is so great that slight variation in its area will cause more or less heat to flow to the secondary radiating tubes 22-22. The internal radiant functions in an important manner in co-action with the external radiant and by variations in its size relative to the external radiant and the nature of its surface, large variations in temperature of the external radiant are effectively obtained. I prefer to

construct the external radiant of the highest heat resistant alloy of thinnest practicable gauge. I specifically refer to the use of ferrous alloy, but, of course, do not wish to be limited in this respect. The secondary radiant can be made of clay of high refractory and radiating qualities capable of withstanding very high heat. Its use, in general, has the following advantages: First, it confines the high temperatures to a comparatively small area; secondly, the secondary radiating surfaces are not subject to excessive temperatures and may, therefore, be constructed of lighter materials than heretofore possible; thirdly, the secondary radiating surfaces may be reduced from 25% to 50% in area, according to the temperature employed and the area of the external radiant of this heater unit; fourthly, it reduces the oxidizing effect on the radiating surfaces because of the lower temperature of the gases after leaving the space between the two radiants; fifthly, it makes possible the construction of a heater unit which may be used over longer periods of time than heretofore.

The screen 72 extends a considerable distance in front of the fireplace, and the upper edge thereof is at a lower elevation than the wall W of the fireplace. In consequence, a maximum amount of radiant heat and light may freely enter the room when fuel is being burned in the grate. It is ordinarily intended that when it is desired to exclusively utilize the combustion gases and flame from the grate of the fireplace, the valve 36 be entirely closed so as to destroy communication between the heating unit 27 and the fire tube 53. I do not mean by this that fuel cannot be burned in the grate simultaneously with the burning of gas at the burner 33; for it is an object of the invention that provision be made herein for so doing at the option of the user. However, most desirable results can be obtained by using the heat generating sources separately.

It should be understood that when the grate fire is used, the valve 36 may be adjusted so that when the gas is fully turned on the valve 36 is opened just enough to permit the proper draft at the point of combustion.

Among incidental features of novelty, the invention provides (1) an economical method for utilizing combustion gases and all available heat with marked efficiency and effectiveness; (2) an organization of parts designed to replace the usual andirons and screen of the fireplace; (3) a structure of light weight which may be easily and quickly installed or removed as desired by the mere skill of the average person; (4) a structure which appears as an ornament when installed.

What is claimed is:

1. A heater comprising the combination with a pair of substantially dome-shaped hollow radiants, one of which is contained within the other and spaced apart from the walls thereof, and a burner co-acting with said radiants to deliver a flame into the space between same from the bottom thereof, the inner radiant being open at its bottom and provided with an opening at one side, of a drum opening into the hollow portion of the inner radiant and into which hot combustion gases are adapted to be discharged therefrom, and a hot air conduit open at both ends and passing through the drum.

2. A heater comprising the combination with a pair of substantially dome-shaped hollow radiants, one of which is contained within the

other and spaced apart from the walls thereof, and a burner co-acting with said radiants to deliver a flame into the space between same from the bottom thereof, the inner radiant being open at its bottom and provided with an opening at one side, of a drum opening into the hollow portion of the inner radiant and into which hot combustion gases are adapted to be discharged therefrom, a hot air conduit open at both ends and passing through the drum, and a vertical hot air riser in which the aforementioned domes are contained and into which said one end of the hot air conduit opens.

3. A portable heater for open fireplaces comprising a pair of vertical risers and a hollow portion connecting one of said risers with the other, a hot air conduit leading through the connecting portion and having its ends opening into the respective risers at the lower ends thereof, a drum contained in the connecting portion and through which the conduit passes, a burner at the lower end of one of the risers, a hollow radiant co-operable with the burner and opening into said drum for the discharge of hot

combustion gases thereto, and means at the lower end of the other riser for forcing air through said hot air conduit into the lower end of the first said riser, the first said riser having a hot air outlet, and draft flue extending from the drum and adapted to be extended into a fireplace, as and for the purpose set forth.

4. A portable heater for open fireplaces comprising a pair of vertical risers and a hollow portion affording communication between the risers; a hot air conduit extending through said hollow portion and having its ends opening into the lower ends of the respective risers; a drum surrounding the conduit; a burner at the lower end of one of the risers for passing hot combustion gases through the drum; and means at the lower end of the other riser for forcing air through said conduit and into the lower end of the first named riser; said first named riser having a hot air outlet; and a draft flue extending from the drum and adapted to be disposed in a fireplace.

WILLIAM E. JONES.
